UNITED STATES PATENT OFFICE.

DANIEL T. FOLEY, OF PHILADELPHIA, PENNSYLVANIA.

CARPET-FASTENING.

SPECIFICATION forming part of Letters Patent No. 761,467, dated May 31, 1904.

Application filed March 5, 1904. Serial No. 196,716. (No model.)

To all whom it may concern:

Be it known that I, DANIEL T. FOLEY, a citizen of the United States, residing in the city and county of Philadelphia, State of Pennsylvania, have invented a new and useful Improvement in Carpet-Fastenings, of which the following is a specification.

My invention consists of a carpet-fastening formed of a doubly-threaded screw one end of which is adapted to be screwed into the riser of a stair or the floor of an apartment and a head adapted to be fitted on the exterior threads of said screw and tighten and control the carpet, the outer end of the screw being adapted for the application of a screw-driver or other tool thereto for rotating the screw, said end appearing at the exterior of said head, so as to be accessible without removal of the latter and said end not limiting the tightening action of said head.

It also consists of a prong adapted to cover the outer end of the screw and permit the carpet to be pierced by the same prior to its location on said screw.

Figure 1 represents a front view of a fastening for stair-carpet embodying my invention. Fig. 2 represents a vertical section thereof on line *xx*, Fig. 1. Fig. 3 represents a section of a prong which is fitted over the exterior portion of the screw as a sheath, so as to admit of the passage of the carpet over the blunt end of the screw. Fig. 4 represents a plan view of a floor-carpet fastening embodying my invention.

Similar letters of reference indicate corresponding parts in the figures.

Referring to the drawings, A designates a screw which has at one portion the thread B, by which it may be screwed into the wood of a stairs or floor, and on the other portion the thread C, on which may be screwed or fitted the head D, which is interiorly threaded after the manner of a nut. The outer end of the screw is blunt and has formed therein the nick E for the engagement of a screw-driver or other tool, so as to drive the screw into position, adjust the same, and remove it when so required.

F designates a prong, which is connected with the sleeve G, the latter being adapted to

be fitted over the exterior portion of the screw A and cover the blunt end of the latter, whereby the carpet may be pierced by the same in its location on the stud.

The operation is as follows: The screws are driven into the risers at opposite ends thereof. Prongs are placed on the exposed ends of said screws and the stair-carpet presented to said prongs and forced over and pierced by the same, so as to be slipped upon the screws, said prongs then being removed. The stair-rod H is then applied over the screws, and the heads D are fitted on the screws and tightened against said rod, whereby the carpet is nicely held and controlled.

It will be noticed that the nicks on the end of the screw are exposed, and so the screws may be moved in or out according to requirements without removing the heads D, and the latter may be most firmly tightened against the stair-rod without being controlled by the outer ends of the screws, the openings in said heads extending entirely through the same.

When it is desired to fasten floor-carpets, screws such as the above are driven into a floor, the prongs are applied, and the carpet pressed over said prongs, after which the latter are removed and the heads fitted on the projecting portions of the screws and tightened, said heads pressing against the washers J, as in Fig. 4, said washers in this case being somewhat of the form of rosettes or other ornamental shape and being substituted for the stair-rods of the other figures.

Various changes may be made in the details of construction shown without departing from the general spirit of my invention, and I do not, therefore, desire to be limited in each case to the same.

Having thus described my invention, what I claim as new, and desire to secure by Letters Patent, is—

1. In a carpet-fastening, a screw having its outer end blunt and a nick in said end, and a head having an interiorly-threaded opening adapted to engage the outer portion of said screw, said opening extending entirely through said head and said nick appearing through said opening.

2. In a carpet-fastening, a screw having a

blunt head, a sleeve adapted to be removably fitted over said head, and a piercing-point carried by said sleeve on the outer end thereof.

3. In a carpet-fastening consisting of a screw adapted to be driven into a stair or floor and having a threaded portion projecting outside of the latter, the outer end of said screw being blunt, and a threaded head

adapted to be fitted on said projecting portion, a prong adapted to be removably fitted on said portion and cover said blunt end.

DANIEL T. FOLEY.
